1,733,994 A * 10/1929 Lalanne B65B 13/18
226/160

FIG. 3 is a top view thereof;

FIG. 4 is a bottom view thereof;

FIG. 5 is a right side view thereof;

FIG. 6 is a left side view thereof;

FIG. 7 is a perspective view thereof;

FIG. 8 is a reference view showing the wire gripper in use; and,

FIG. 9 is a reference view of the wire gripper in an alternate position of use.

The broken lines in the figures represent environment and portions of the wire gripper that form no part of the claimed design.
